ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

SAW-VISE.

1,106,401.

Specification of Letters Patent. Patented Aug. 11, 1914.

Application filed December 10, 1913. Serial No. 805,832.

To all whom it may concern:

Be it known that I, ALBERT A. PAGE, a citizen of the United States, residing in the town of East Haven, county of New Haven, 5 and State of Connecticut, have invented certain new and useful Improvements in Saw-Vises, of which the following is a full, clear, and exact description.

This invention relates to saw vises, and 10 the primary object is to provide a compact, efficient device which may be readily and inexpensively manufactured.

To this and other ends, the invention consists in the novel features and combinations 15 of parts to be hereinafter described and claimed.

In the accompanying drawing, Figure 1 is a front elevation of a saw vise embodying my improvements, showing it applied to a 20 board, or like supporting member; Fig. 2 is a rear elevation of the vise detached; Fig. 3 is a top plan view of Fig. 1; Fig. 4 is an end view of the vise; Fig. 5 is an enlarged section on line 5—5 of Fig. 4; and Fig. 6 is an enlarged section on line 6—6 of Fig. 3.

My improved saw vise comprises in its main features a frame, adapted for application to a suitable supporting member, and having a fixed elongated jaw, a movable 30 jaw guided laterally in the end portions of the frame for movement toward and away from the fixed jaw, and cam devices mounted in the ends of the frame for clamping the movable jaw on the saw, or other work.

Referring to the drawing, 10 is a frame, composed of an elongated bar, having a downwardly projecting flange 11, adapted to be screwed to the edge of a board 12, or other supporting member. Extending rear- 40 wardly from the frame 10 and forming an integral extension thereof is a flange or web 13, adapted to be screwed to the top of the board or support 12, as shown in Fig. 3. The frame 10 and the flanges or webs 11, 13

45 may be conveniently formed by casting them as an integral structure. At its respective ends, the frame 10 is provided with substantially U-shaped keeper portions 14 (Fig. 6), lying in a vertical plane, and presenting upper and lower guide surfaces 15, 16, for a movable jaw 17. Extending upwardly and forwardly from the upper legs 14 of the keeper portions 14 are arch mem- 50 bers 18, located in vertical planes directly 55 transversely to the keeper portions 14, and

to the longitudinal axis of the device. The keeper portions 14 are preferably cast integral with the frame 10, and form a part thereof, and by preference the forwardly projecting arches 18 will likewise be cast 60 integral with the keeper portions and frame. The lower ends of the arches 18 are connected preferably in an integral manner by a fixed jaw 19, located in alignment with the guides in the keepers 14, and opposing the 65 jaw 17, which is movable in said keepers. It will be noted that the fixed jaw 19 is outermost with reference to the frame 10, and that the movable jaw 17 is innermost. By supporting the fixed jaw from above, by 70 means of the arches, or brackets, 18, the saw or other work may be readily inserted between the jaws from beneath in an obvious manner.

Extending rearwardly from each end of the frame are horizontal lugs 20, which form bearings for a cam 21, whereby the movement of the corresponding end of the jaw 17 is controlled. In the form shown, a vertical pin 22 connects each pair of 75 lugs 20, and the cam or eccentric 21 is rotatable about the pin 22 in a horizontal plane, and adapted to engage a surface 23 at the rear edge of the extremity of the movable jaw. A rod 25 is secured to 80 each cam for facilitating manipulation thereof by the operator.

Referring to Fig. 3, it will be noted that when the rods 25 extend toward each other, the cams at the respective ends of the vise 90 are in position to release the movable jaw. This permits separation of the jaws by means of springs 26 interposed between the end lugs 27 on the jaw 17 and the rear faces of the respective keeper portions 14, as 95 shown in Fig. 5. When the rods 25 are moved into the position shown in dotted lines in Fig. 3, the cam surfaces of the cams will force the movable jaw toward the fixed jaw by engagement of the cam surfaces with 100 the rear edge of the movable jaw terminals.

The device is compact and easily portable, and the construction is quite simple, as it merely involves a main frame casting, a movable jaw, and simple but efficient jaw 105 actuating means.

Without limiting myself to the construction shown, I claim:

1. In a saw vise, the combination of a frame having upwardly and inwardly 110

- turned guide portions at the ends, a jaw movable transversely of the frame and having its ends engaged with the respective guide portions, a second jaw, brackets extending forwardly from the upper parts of the respective guide portions, and supporting said second jaw rigidly in front of said movable jaw, and means for adjusting said movable jaw; substantially as described.
- 10 2. In a saw vise, the combination of a frame, guide portions on the respective ends of the frame, turned upwardly and inwardly in substantial parallelism with the longitudinal axis of the frame, and providing in conjunction with the frame upper and lower guide surfaces at each end of the latter, a jaw movable transversely of the frame, and having upper and lower surfaces at each end thereof engaging the corresponding upper and lower guide surfaces, brackets extending forwardly from the respective guide portions, a fixed jaw supported from above by said brackets, and located in front of said movable jaw, and means for adjusting the movable jaw; substantially as described.
- 15 3. In a saw vise, the combination of an elongated frame, upwardly and inwardly turned guide portions at the respective ends of the frame, located in substantial parallelism to the longitudinal axis of the frame, a jaw movable transversely of the frame, at the upper surface of the latter, and having at its respective ends upper guide surfaces engaging said guide portions, extensions on the respective ends of the movable jaw, facing the upright parts of the guide portions, springs interposed between the respective extensions and the respective upright parts of the guide portions, a fixed jaw rigidly supported from the frame, and means for adjusting the movable jaw relatively to the fixed jaw; substantially as described.
- 20 4. In a saw vise, the combination of an elongated frame, upwardly and inwardly

turned guide portions on the respective ends of the frame, substantially parallel to the longitudinal axis of the frame, a jaw movable transversely of the frame, and having its ends engaged with the respective guide portions, springs interposed between said guide portions and said jaw, brackets integral with said guide portions, a fixed jaw carried by said brackets in front of said movable jaw, said springs normally separating the jaws, and means for clamping the movable jaw on the work in opposition to said springs; substantially as described.

25 5. A saw vise, comprising a frame having upwardly and inwardly turned keepers at the respective ends, brackets projecting forwardly from said keepers, a fixed jaw, supported by and extending between said brackets, a movable jaw guided transversely of the frame in said keepers, springs interposed between the keepers and opposing portions of the movable jaw, and normally separating the jaws, and means supported on the frame, to engage the movable jaw, and move it toward the fixed jaw in opposition to said springs; substantially as described.

30 6. In a saw vise, the combination of an elongated frame, a jaw extending lengthwise of said frame, at the upper part of the same, and movable transversely of said frame, portions integral with the frame extending inward over the ends of said jaw to guide the jaw between said portions and the frame, a second jaw, forwardly extending brackets integral with said guide portions and supporting said second jaw rigidly in front of said movable jaw, and means for adjusting said movable jaw; substantially as described.

In witness whereof, I have hereunto set my hand on the 8th day of December, 1913.

ALBERT A. PAGE.
